CAVITY RESONATOR STRUCTURE AND
TUBE EMPLOYING THE SAMEPercy L. Spencer, West Newton, Mass., assignor to
Raytheon Manufacturing Company, Newton,
Mass., a corporation of Delaware

Application October 7, 1950, Serial No. 189,018

4 Claims. (Cl. 315—40)

1

This invention relates to cavity resonator structures and to electron-discharge devices of the type, for example, magnetrons, employing such structures.

It is well known that tubes designed for the generation of electrical oscillations in the microwave region of the electromagnetic spectrum, and incorporating multiple frequency-determining cavity resonators for this purpose, have a tendency to oscillate at modes other than the desired mode. The undesired modes represent a waste of energy and it has heretofore been proposed to suppress them by a method known as strapping.

This consists, broadly speaking, of interconnecting, by low-impedance means, points in the high-capacitance regions of the multiple cavity resonators intended during oscillation simultaneously to be of like phase.

However, due to space limitations, strapping is not always feasible. Furthermore, and particularly in high power tubes, the strapping means is sometimes called upon to carry excessively high currents.

It is also well known that, in tubes of the type above referred to, variations in the external load have a marked pulling effect upon the frequency for which the tube is designed.

It is, therefore, among the objects of the present invention to eliminate the foregoing disadvantages by providing a cavity resonator structure which may be conveniently used, for example, in electron-discharge devices of the magnetron type, and which successfully suppresses spurious oscillations without the necessity of any strapping.

It is another object of the present invention to provide a cavity resonator structure which is so constructed as to minimize the pulling effect of variations in the external load.

It is a further object of the present invention to provide a cavity resonator structure which may be employed as aforesaid, and which is simple in construction and easy and economical to fabricate and assemble.

These, and other objects, which will become more apparent as the detailed description of the present invention progresses, are attained, briefly, in the following manner.

The cavity resonator structure of the present invention includes a plurality of conductive members each of which partially encloses a region of space and, preferably, is of a substantially resonant electrical length peripherally about said region of space. If desired, some of said con-

2

ductive members can be of different resonant electrical lengths as are the elements of the cavity resonator structures of the so-called rising sun type. Each of said conductive members has at least one portion thereof extending into the region of space enclosed by the immediately adjacent conductive member. Preferably, the conductive members are of substantially U-shaped transverse section, and are each provided with longitudinally slotted portions which straddle oppositely longitudinally slotted portions of immediately adjacent conductive members.

When incorporated in an electron-discharge device, for example, of the magnetron type, the cavity resonator structure of the present invention may constitute the anode of said device, and the above referred to conductive members thereof may be circumferentially disposed to define a central space receptive of the cathode of said device.

In the following specification there shall be described, and in the accompanying drawing shown, illustrative embodiments of the cavity resonator structure, and tube employing the same, of the present invention. It is, however, to be clearly understood that the present invention is not to be limited to the exact details herein shown and described for purposes of illustration only, inasmuch as changes therein may be made without the exercise of invention and within the true spirit and scope of the claims hereto appended.

In said drawing:

Fig. 1 is a longitudinal sectional view taken substantially through the center of a magnetron incorporating a cavity resonator made in accordance with the present invention;

Fig. 2 is a transverse sectional view taken on line 2—2 of Fig. 1;

Fig. 3 is a fragmentary perspective view of a portion of the anode of said magnetron; and

Fig. 4 is an enlarged, further fragmentary perspective view of the same showing more clearly the manner in which the conductive members above referred to are intercoupled.

Referring now more in detail to the aforesaid illustrative embodiment of the present invention, with particular reference to the drawing illustrating the same, the numeral 10 generally designates an electron-discharge device of the magnetron type. Said device comprises an anode structure 11, a cathode structure 12, and magnetic means 13 for establishing a magnetic field between said anode and cathode structures, in a direction transverse to the electron path therebetween.

In the device shown, the anode structure 11

includes a hollow cylindrical body 14, made of highly conductive material, such as copper, the inner wall of said body being provided, in the longitudinal mid-region thereof, with a multiplicity, here shown as ten, of shallow arcuate depressions 15. Secured in each such depression 15, and extending radially inward from the body 14, is a substantially U-shaped conductive member 16, each such member 16 partially enclosing a region of space 17 in advance thereof and being of a substantially resonant electrical length, for example, a half wave length, peripherally about said region of space. Each conductive member 16 thereby constitutes a cavity resonator.

As best seen in Fig. 4 of the drawing, each conductive member 16 is provided, adjacent the yoke portion thereof, with a longitudinal slot 18, adjacent conductive members having their respective slots oppositely disposed, whereby the arm portions 19 of said members may straddle each other and extend into the region of space 17 of the immediately adjacent member.

This arrangement affords tight inductive coupling between the individual cavity resonators provided by the multiple conductive members 16, as a result of which the structure tends to lock in at the desired mode of oscillation, namely, the π mode, in which successive arm portions 19 of each member 16 are 180° out of phase with respect to each other, the frequency of this mode being determined, primarily, by the electrical length of said members 16, as above stated, peripherally about the space enclosed thereby.

Furthermore, the aforesaid tight inductive coupling between the individual cavity resonators reduces to a negligible amount the frequency pulling effect of external loading conditions.

The anode structure 11 is closed at its ends, for example, by end plates 20 and 21, with the junctions between the cylindrical body 14 of said structure, and said plates 20 and 21, being hermetically sealed, as at 22.

The conductive members 16 are, preferably, circumferentially disposed to provide a central space 23 which is receptive of the cathode structure 12. The latter, which is coaxial with the anode structure 11, includes a cathode sleeve 24, conventionally made of nickel, or the like, provided with a reduced portion 25 the length of which, preferably, is coextensive with the longitudinal dimension of the arm portions 19 of the conductive members 16, said reduced portion 25 being provided with a highly electron-emissive coating, for example, of the well known alkaline-earth metal oxide type.

In order properly to support the cathode sleeve 24 with respect to the arm portions 19 of the conductive members 16, said sleeve may be reduced, as at 26, to fit into an elongated, electrically conductive tubular member 27 having, at its outer end, a ferrule 28 closed by a glass seal 29. Said seal, together with one or more glass beads 30 disposed within said tubular member 27, supports a lead-in conductor 31 which passes through said tubular member and has its upper end connected, as at 32, to one terminal of a cathode heating filament 33. The other terminal of said filament may be connected, as at 34, to the cathode sleeve 24.

In order to convey current to the filament 33, the lead-in conductor 31 is connected by a conductor 35 to one terminal of a suitable source of voltage (not shown), the other terminal of said source of voltage being connected by a con-

ductor 36 to a heat dissipating member 37 fixed upon the lower end of the tubular member 27.

In order to properly support the cathode structure 12, and insulate the same from the anode structure 11, the tubular member 27 may have fixed thereto a cup-like bushing 38 sealed into one end of a glass tube 39, the other end of said glass tube having sealed therein a tubular bushing 40, in turn, secured to a tubular pole piece 41 constituting one of the components of the magnetic means 13.

Said pole piece 41 may be hermetically sealed, as at 42, into the end plate 21 and be provided with a central bore 43, whereby the cathode structure 12 may enter the device.

Another pole piece 44, provided with a recess 45 receptive of the upper end of the cathode structure 12, may be hermetically sealed, as at 46, into the end plate 20, said pole piece and the pole piece 41 being fixed, for example, at the opposite ends of a horseshoe magnet 47 (only partially shown), whereby an appropriate magnetic field may be established, as previously indicated, between the anode structure 11 and cathode structure 12.

By suitably heating the cathode, and applying a power potential difference between said cathode and the anode, the device can be made to generate electrical oscillations of a wave length determined by the capacitance and inductance built into said device as a function of the geometry thereof, and more especially, of the dimensions of the above referred to cavity resonators defined by the conductive members 16 of the anode structure.

In order to extract power from the device, a loop 48 may be introduced into one of the cavity resonators provided by the conductive members 16, said loop coupling with the magnetic component of the generated electrical oscillations. While not specifically shown, the loop may be connected to the inner conductor of a coaxial transmission line, the outer conductor of said transmission line being connected to an outlet pipe 49. It is to be understood, of course, that the inner and outer conductors of the transmission line will have an appropriate hermetic seal therebetween so as to maintain the usual vacuum within the anode structure 11.

This completes the description of the aforesaid illustrative embodiments of the present invention. It will be noted from all of the foregoing that there has been provided a cavity resonator structure which is especially useful in electron-discharge devices of the magnetron type, which cavity resonator structure includes multiple cavity resonators which are tightly inductively coupled, whereby spurious oscillations are suppressed without the necessity of the strapping arrangements which have heretofore been proposed for this purpose and external loading conditions have very little pulling effect on the frequency at which the device is intended to operate. It will also be noted that construction of the present invention is simple and may be economically fabricated and assembled.

Other objects and advantages of the device of the present invention will readily occur to those skilled in the art to which the same relates.

What is claimed is:

1. A cavity resonator structure comprising: a plurality of strap-like conductive members each of which is of substantially U-shaped transverse section; each of said conductive members having

longitudinally slotted portions straddling oppositely longitudinally slotted portions of the immediately adjacent conductive members and extending into the regions of space enclosed by said immediately adjacent conductive members.

2. An electron-discharge device comprising: a cathode; an anode structure spaced from and surrounding said cathode; said anode structure including a plurality of circumferentially disposed conductive members defining a central space receptive of said cathode; each of said conductive members partially enclosing a region of space; and each of said conductive members having portions thereof extending into the regions of space enclosed by the immediately adjacent conductive members.

3. An electron-discharge device comprising: a cathode; an anode structure spaced from and surrounding said cathode; said anode structure including a plurality of identical, circumferentially disposed conductive members defining a central space receptive of said cathode; each of said conductive members partially enclosing a region of space; successive conductive members having oppositely slotted portions which mutual-

ly straddle each other and extend into the regions of space enclosed by the immediately adjacent conductive members.

4. An electron discharge device comprising: a cathode; and an anode spaced from said cathode; said anode including a substantially U-shaped space-confining member the end edges of which extend, respectively, into spaces confined by adjacent, similar U-shaped anode members and face said cathode.
